(57) **CLAIM**

The ornamental design for a fiber optic 45 degree corner, as shown and described.

DESCRIPTION

FIG. 1 is a perspective view of a fiber optic 45° corner, showing our new design and taken from a top, back, side vantage;

FIG. 2 is a front elevation thereof;

FIG. 3 is a top plan thereof;

FIG. 4 is a side view thereof, as taken from the left side; FIG. 5 is a side view thereof, as taken from the right side; and,

FIG. 6 is a back elevation thereof.

Broken-line showings of pintles extending from the fiber optic 45° corner are illustrative only and form no part of the claimed design.
